UNITED STATES PATENT OFFICE.

JOHN A. ARTON, OF CHICAGO, ILLINOIS.

SOFA-BED.

1,269,772.

Specification of Letters Patent. Patented June 18, 1918.

Application filed November 30, 1914. Serial No. 874,586

To all whom it may concern:

Be it known that I, JOHN A. ARTON, a citizen of the United States, residing at the city of Chicago, in the county of Cook and State of Illinois, have invented certain new and useful Improvements in Sofa-Beds, of which the following is a specification.

My invention relates to the articles of furniture sometimes known as sofa beds, which may be converted by a change in the relation of their parts from a sofa into a bed, or from a bed into a sofa. These articles of furniture are so constructed that an upholstered back and seat are provided when the same is in use as a sofa, but by a change of parts the elements of a bed, including the framework and springs, are disclosed, together with necessary mattress and other bedding. My invention comprises various features of construction by which the manufacture is simplified and cheapened, while at the same time the action of the parts is more direct and positive. The transformation from one form to another is light and easy, while the various parts are made to coöperate in such action. It also consists in certain other separate devices and combinations which are herein-after fully set forth in the description and claims. The principles of my invention are illustrated in the drawings, in which—

Figure 1 shows a vertical section, the end being removed to disclose the working parts, the same being in their normal positions to be used as a sofa;

Fig. 2 is a similar view showing the moving parts shifted and extended for use as a bed;

Fig. 3 is a detailed top view of one end of the same shown in Fig. 2.

Further describing my invention with reference to the drawings, in which like characters of reference denote like parts throughout: 1 and 2 are respectively the front and rear legs of a davenport frame. 3 and 4 are the arm and leg pieces by which the front and rear legs are connected. 5 is a facing strip connecting the front legs, and which may be suitably finished to correspond

to the general exterior finish of the sofa. 6 is a tie strip connecting the rear legs. 7 is a stationary cover for the top of the back. 8 represents a seat with upholstering. 9. 10 represents a back with upholstering 11, and pivotally attached to the seat by a hinge 12 adjacent their proximate edges. The side members 13 of the primary or seat section are secured to the normally underside of the seat and have projections 13', which terminate in hinges 14. To the said hinges are attached the side members 15 of the secondary bed section. Said members 15 are connected to the back 10 by a flexible shackling device consisting of the member 17 pivoted to the seat at 18 and the member 19 pivoted to the bed frame member 15 at 20. Said members are hinged or pivoted together at 21, and the member 19 is provided with a hooked extension 22 for a purpose to be hereinafter described. A swinging link 25 has one end pivoted at 26 to the end piece 4. The other end of said link may be provided with a slot 25' and a pin 25" transverse to said slot, while the seat is provided with a trunnion or pivot 27, upon which it rests at the other end of said link and within the slot. The movement of the seat in either direction is limited by the stops 29 and 30, between which the links 25 swing and with which they engage.

When thus mounted, the seat will have a possible movement from front to rear, which is determined by the said stops, although in practice a slight variation or flexibility of such movement is added by reason of the play of the trunnions 27 within the slot 25', such play being limited by the transverse pin 25". This construction further provides means by which the seat with its attachments may be readily mounted upon or dismounted from the supporting frame. A stop 31 is attached to the inner face of the bed frame projecting inwardly toward the seat. A lug 32 is secured to the end of the seat in such a position that when the same is advanced to its limit of movement the said lug will rest on the said stop.

A similar lug 35 is secured to the end of the seat on the other side of the trunnion 27, in such a position that when the seat is inverted on said trunnion 27, the said lug 5 will rest upon the stop 31, the seat being at its rearward point of movement as limited by stop 30, but when the seat is pushed back within the limit of the slot 25', the links 25 being in contact with stop 30, lug 10 35 will be disengaged from stop 31. That the relative positions of the pivot 26 and the stops 29, 30 and 31 may be made positive, I provide metallic reinforcement plates 15 36 upon which the said pivots and stops are mounted. Said plates are secured to the inner faces of the pieces 4 which should be recessed to receive them.

When the seat is in its reversed position, and the bed members are extended a further 20 security may be given by the projections 37 under the front and 37' under the back of the seat, which are received within suitable recesses in the upper edge of the facing strips.

25 Securely attached to the side bars 13 of the primary section of the bed frame are transversely extended projections 39, to which are pivotally attached at 40 the side members of a bedding holder having the long 30 arm 41 and the short arm 42. Transversely extended from the side bar 15 of the secondary bed section is a projection 43 spaced a short distance from the hinged connection 14. A tie bar 44 connects the two extensions 35 40 and 43. A spring 45 has one end attached at 46 to the long arm 41 of the bedding holder, while the other end of said spring is attached at 47 to the frame of the davenport. When the parts are in the positions shown in Figs. 1 and 2, the said 40 spring should be under tension.

When it is desired to change the sofa into a bed the seat is slightly lifted, sufficiently to release the engagement of projection 37, 45 and pushed backward upon the link 25, thereby disengaging the stop 31 from the lug 32. Upon taking hold of the upper part of the back and pulling forward, the action will be aided by the tension of spring 50 45, but as the back advances so that the spring passes its dead center the pull of the spring tends to extend and turn the lever 41 upon its pivot 40, thereby giving a thrust upon the tie rod 44 against the extension 43. By the time the device has reached this point in its movement the natural hold 55 of the operator will be on the secondary bed member adjacent to the top of the back, and the pull of the operator will join with the 60 pull of the spring to extend the secondary bed section into alignment with the primary bed section and in the relation to the back shown in Fig. 2.

Legs 48 are pivotally connected to the

side bars 15. This preferably is by means 65 of the upwardly extended member 49 secured thereto, whereby the point of attachment is raised above the side bar. The legs are provided with keyhole slots 49' and a rivet or similar device, having a larger head 70 and flattened body passes the slot in such a manner that when the flattened body is in the narrowed portion of the slot the leg will be held at right angles to the side bar; while when the body of the rivet is in the eye of the 75 slot the leg may be rotated in such body as a pivot. The legs are connected by a flexible brace 50, and are provided with an outwardly projecting pin 51. The said leg is extended upward to form an arm, to which 80 at 52 is pivoted one end of a retaining rail 53. The other end of said retaining rail is pivoted at 54 to one end of a link 55, the other end of which is pivotally connected to the side bar 15. This may be by means of 85 the projection 43 extended transversely of the side bar for that purpose. The link 55 should be somewhat longer than the short arm of the leg 48, and the pivot 54 should be extended inwardly as shown at 54'.

90 In folding the legs and closing the bed to form the sofa the operator may take hold of the leg brace 50 at the same time slightly lifting on the ends of the secondary bed member to free the rivet in the key-hole 95 slot 49', whereupon the legs are rotated, causing the same with the retaining rail and attachments, to assume the folded position shown in the dotted lines. In so doing the flexible brace 50 permits the legs to be bent 100 slightly toward each other and to engage under the projections 54' in which position the natural stiffness of the brace will securely hold them. The brace is thus held upon the mattress and other bedding and 105 forms a bedding holder to keep it securely in place during the time that it is not in use. A further upward and backward movement of the bed section causes the projection 37' to be disengaged and also to allow the seat to ride up on pin 27 in slot 25'. Lug 31 is thus freed from stop 35 and the seat is permitted to turn on the trunnion 27. This movement is aided by spring 45. The 110 secondary bed members 15 turn downwardly 115 on hinges 14, thereby causing arm 41 to fold over the primary bed member 13. When so folded the spring 45 tends to retard the natural turning tendency of the seat in its later movement, while in the final position it 120 aids to hold the bedding holder in place. Meanwhile the change in relation of side member 15 and back 10, as shown in Fig. 2, to the relation shown in Fig. 1, causes the hook 22 to engage with the projection 51 125 on leg 48, forming a further secure lock therefor. For further rigidity and security in the sofa use I provide a hook 56 on the

under side of back 10, which is adapted to engage a stationary member 57 on the leg 2. I claim:

1. In a sofa bed having an extension bed section with side members; the combination therewith of supporting legs for the ends of said members pivoted thereto and foldable to said members, retaining rails on the bed section adapted normally to engagement with the legs, and a flexible strip or rod to connect the said legs and by flexure to cause the disengagement thereof from said retaining rails.
2. In a sofa bed having an extension bed section with side members, the combination therewith of supporting legs pivoted to said members and foldable thereto, retaining rails pivotally mounted on said bed section, means for mutual engagement between the retaining rails and the legs when so folded, and a flexible strip or rod to connect the said legs together and adapted to control the engagement thereof with the said retaining rails.
3. In a sofa bed; a frame, a reversible seat pivotally connected thereto, a back hinged to the seat and movable as the seat is rotated, a bed section pivotally connected to the seat, and a flexible device to connect the back and said bed section.
4. In a sofa bed; a frame, a reversible seat pivotally connected thereto, a back hinged to the seat and movable as the seat is rotated, a primary bed section secured to the seat, a secondary section pivotally connected to the primary bed section, and a plurality of two piece links to connect the secondary bed section to the said back.
5. In a sofa bed; a frame, a reversible seat pivotally connected thereto, a back hinged to the seat and movable as the seat is rotated, a primary bed section secured below the seat, a secondary section pivotally connected to the primary bed section, and a flexible link to connect the secondary bed section to the said back.
6. In a sofa bed; a frame, a reversible seat pivotally connected thereto, a back hinged to the seat and movable as the seat is rotated, a primary bed section under the seat, a secondary section pivotally connected to the primary bed section, legs pivoted to the secondary bed section, links to connect the back and the secondary section, and means for mutual engagement between the links and said legs.
7. In a sofa bed; a frame, a reversible seat pivotally connected thereto, a back hinged to the seat and movable as the seat is rotated, a primary bed section under the seat, a secondary section pivotally connected to the primary bed section, legs pivoted to the secondary bed section and provided with lugs, and links to connect the back and the

secondary section, said links being provided with hooks to engage said lugs.

8. In a sofa bed; a frame, a reversible seat pivotally connected thereto, a back hinged to the seat and relatively movable as the seat is rotated, a primary bed section under the seat, a bedding holder with side members pivotally connected to the side bars of said primary bed section to provide extended short arms, a secondary bed section pivotally attached to the first bed section and having projections transversely extended therefrom, and tie bars to connect the said projections with the short arms of the side members of the bedding holder.

9. In a sofa bed; a frame, a reversible seat pivotally connected thereto, a back hinged to the seat and relatively movable as the seat is rotated, a primary bed section under the seat, projections transversely extended from said primary bed section, a bedding holder with side members pivotally connected to the said projections to form long and short arms, a secondary bed section pivotally attached to the first bed section and having projections transversely extended therefrom, tie bars to connect the said last named projections with the short arm of the side members of the bedding holder, and a spring to connect the long arms thereof to the frame.

10. In a sofa bed; a frame, a reversible seat pivotally connected thereto, a back hinged to the seat and relatively movable as the seat is rotated, a primary bed section under the seat, a bedding holder with side members pivotally connected to the side bars of said primary bed section to provide extended long and short arms, a secondary bed section pivotally attached to the first bed section and having projections transversely extended therefrom, tie bars to connect the said projections with the short arms of the side members of the bedding holder, and a spring to connect the long arms thereof to the frame.

11. In a sofa bed; a frame, a reversible seat pivotally connected thereto, a back hinged to the seat and relatively movable as the seat is rotated, a primary bed section under the seat, projections transversely extended from the side members of said primary bed section, a bedding holder with side members pivotally attached to said projections to form long and short arms, a secondary bed section pivotally attached to the first bed section and having projections transversely extended from the side members thereof, tie bars to connect the said last named projections with the short arms of the side members of the bedding holder, and a spring to connect the long arms thereof to the frame.

12. In a sofa bed having a frame and rear upwardly extended legs, a reversible seat

connected thereto, a back hinged to the seat and forwardly overturnable as the seat is rotated, a hook on the back and an engaging device therefor on the said legs.

5 In witness whereof, I have hereunto subscribed my name, this 28th day of November

1914, in the presence of two subscribing witnesses.

JOHN A. ARTON.
